UNITED STATES PATENT OFFICE.

GEORG SCHOENNER, OF NUERMBERG, GERMANY.

DRAWING-PEN.

1,143,730.

Specification of Letters Patent. Patented June 22, 1915.

Application filed December 9, 1912. Serial No. 735,614.

To all whom it may concern:

Be it known that I, GEORG SCHOENNER, a subject of the German Emperor, residing at Nuremberg, Bavaria, Germany, have invented 5 certain new and useful Improvements in Drawing-Pens, of which the following is a specification.

My invention relates to improvements in mathematical drawing instruments.

10 It refers particularly to that class of drawing-pens which, when temporarily opened for cleaning, and closed again, will assume the original distance between the pen blades, so that the draftsman is directly able to continue drawing lines of the same width as before without readjustment of the pen.

15 The invention is illustrated in the accompanying drawings in which:

Figure 1 represents in side elevation a closed drawing-pen which embodies in desirable form the present improvements. Fig. 2 is a similar elevation of an open drawing-pen. Fig. 3 shows in plan view the inner side of a sliding bar. Fig. 4 shows in similar 25 view the inner side of the nether blade. Fig. 5 is a cross section on the line E—F of Fig. 1. Fig. 6 is a cross section on the line G—H of Fig. 1. Fig. 7 is a face view of a part of a modification of the drawing-pen. Fig. 8 is a partial longitudinal section through a 30 closed pen and Fig. 9 a similar partial section through an opened pen of this modification; and Figs. 10, 11, 12 are corresponding views showing slight changes in the 35 modified form of pen.

Similar characters denote like parts in all the figures.

In the drawing-pen illustrated the adjusting screw 2 carries the little hand-wheel 3 40 and has a neck 14. The screw passes through an opening 19 in the nether blade 7. At the lower rim of the neck 14 there is a flange 15 which seats in a socket in the blade 1, see Figs. 1, 3 and 5. Thus the screw 2 is permitted to turn, but not to move in axial direction.

At the end of the screw 2 there is a nut 16 having a neck 17 and underneath an enlargement 18. The nether blade 7 has a slot 50 19 which is sufficiently wide for the passage of the enlargement 18 of the nut 16 and further a longitudinal perforation 20 through which passes freely a headed screw 21. The head 22 of this screw is on the outside of the blade 7 and acts as a handle for the adjustment of a sliding bar 23. The screw 21 is

screwed into the sliding piece 23 which is on one of the faces of the blade 7. At some distance from the screw 21 a short screw 24 is inserted in the sliding-piece 23, said pin 60 24 extending into the slot 20, but not through the same. This pin which need not necessarily be screw-threaded and may be replaced by any ordinary pin or detent, serves to secure the sliding piece against turning 65 about the screw 21. At its other end the said sliding piece is shaped to form a claw 25 shown in detail in Fig. 3. This claw frictionally fits on the neck-portion 17 of the nut 16.

70 In the modification shown in Figs. 7 to 9 the hand-wheel 3 is fastened upon the adjusting screw 2 between the two blades of the drawing-pen. The adjusting screw 2 is adapted to slide in a slot 27 of the nether 75 blade 7. The nut 16 screwed upon the screw 2 slides in the slot 28 of the blade 1. The said slot 28, the width of which corresponds with the diameter of the nut 16, has on one end a widened portion 29 permitting of the 80 passage of the enlarged edge 30 of the nut 16.

I adjust this drawing-pen by turning the small wheel 3. This causes a rotation of the screw 2 while the nut 16 is prevented from turning by the clamping action between the 85 same and the blade 1. To open the drawing-pen I move the wheel 3, the screw 2 with its head 26 and the nut 16 in the direction of the arrow α shown in Fig. 8 until the nut 16 has arrived in the wide portion 29 90 of the slot 28 and its edge 30 passes through the said wide portion 29 (see Fig. 9). To close the pen I press the blades 1 and 7 together and move the intermediate parts in opposition to the direction required for 95 opening the pen until the nut 16 and blade 1 are again engaged. Neither during the opening nor the closing of the pen is there any turning of the hand wheel or the screw 2 relative to the nut 16, so that the width or 100 thickness of the line remains unchanged.

The difference between the modification shown in Figs. 10 to 12 and that shown in Figs. 7 to 9 is merely that in the former the hand-wheel is not between the blades, but 105 on the outside. The hand-wheel 3 is secured to the end of the screw 2 on which there is further provided an enlargement 31 in such a way that between the same and the hand-wheel 3 the screw is adapted to 110 slide in the slot 27. The adjustment of the pen is accomplished by turning the hand-

wheel 3 and the screw 2. On moving the intermediate parts in the direction of the arrow α shown in Fig. 11 the blade 7 and the nut 16 become disengaged, because the enlarged edge 30 passes through the wide portion 29 of the slot 28. Thus there is also, in this case, no change in the thickness of the line caused by an opening or closing of the drawing-pen.

10 As hereinbefore described the drawing-pens forming the subject matter of the present invention are provided each with a set screw and an interiorly threaded nut located at the end portion of the set screw, said adjusting screw and the nut being freely passable through the nether blade and the nut being adapted to be locked to the nether blade of the drawing-pen and released therefrom, whereby the adjustment of the pen for 15 drawing lines of a certain width is retained and remains unchanged when the pen blades are locked again after the same were opened say, for the purpose of cleaning by moving the locking means to inoperative position.

20 25 I claim as my invention:

1. A drawing-pen retaining its adjustment for a width of line, comprising a pen blade, a headed set screw passing freely through said blade, a threaded nut located 30 at the end of the set screw, a second pen blade, the set screw and the nut being wholly free of said second blade and means in the second blade for locking the nut thereto, said locking means and the screw being relatively movable to bring the nut into and out 35

of locking engagement with the locking means.

2. A drawing-pen retaining its adjustment for a width of line when closed again after cleaning, comprising a pen blade, a headed set screw passing freely through said blade, a threaded nut located at the lower end of the set screw, and having an enlarged locking bottom portion, a second pen blade, the set screw and the nut being 40 wholly free of said second blade and means in the second blade for locking the nut thereto, said locking means and the set screw being relatively movable to bring the nut into and out of locking engagement with the 45 locking means.

3. A mathematical drawing-pen retaining its adjustment for a width of line when closed again after cleaning, comprising a pen blade, a headed set screw swiveled in 55 said blade, a threaded nut at the lower end of the set screw having a neck and an enlarged locking bottom portion, a second pen blade, the set screw and the nut being freely passable through said second blade and locking means in the second blade, said locking means being movable to inoperative position.

60 In testimony whereof I affix my signature in presence of two witnesses.

GEORG SCHOENNER.
